UNITED STATES PATENT OFFICE.

FRANK KOSINSKY, OF BROOKLYN, NEW YORK.

LOCK.

1,134,141.

Specification of Letters Patent.

Patented Apr. 6, 1915.

Application filed August 22, 1914. Serial No. 857,989.

To all whom it may concern:

Be it known that I, FRANK KOSINSKY, a subject of the Czar of Russia, residing at Brooklyn, in the county of Kings and State of New York, have invented certain new and useful Improvements in Locks, of which the following is a specification.

This invention relates to certain new and useful improvements in locks, and has for its primary object to provide a lock of simple and effective construction which will necessitate the employment of a particular form of key, and a knowledge of how to manipulate the key within the lock casing to release the locking bolt.

The invention resides in the novel combination and construction of parts as will be hereinafter more fully described and then claimed, and in describing the invention in detail, reference will be had to the accompanying drawings showing a practical embodiment of my invention wherein like numerals will be employed to designate like parts throughout the several views of the drawings, in which:—

Figure 1 is a view partially in side elevation and partially in longitudinal section of a lock constructed in accordance with my invention, the front plate of the lock casing being removed and the lock bolt being shown in locked position. Fig. 2 is a similar view showing the key as having been operated to raise the locking pins into position to permit the withdrawal of the locking bolt. Fig. 3 is a view similar to Figs. 1 and 2, showing the locking bolt retracted into unlocked position and illustrating the manner in which certain of the locking pins hold the bolt against being projected until again properly operated. Fig. 4 is a transverse vertical sectional view of a lock in accordance with my invention. Fig. 5 is a perspective view of the lock casing with the front plate and with all of the movable parts of the lock removed. Fig. 6 is an inverted perspective view of the locking bolt. Fig. 7 is a perspective view of one of the locking pins. Fig. 8 is a perspective view of the key employed in connection with the lock, and Fig. 9 is a perspective view of the spring member which bears upon the locking pins.

To put my invention into practice I provide a lock casing consisting of a rear plate 10, top wall 11, bottom wall 12, a front end wall 14, a rear end wall 15 and a front or cover plate 16, the latter being removable,

being secured to the casing by screws or any other manner.

Within the lock casing is provided a longitudinally extending pin supporting bar 17 suitably fixed within the casing, and may be cast integral therewith. This pin supporting bar is provided intermediate its ends, preferably closer to the forward end than to the rear end, with a series of pin receiving apertures which may be in any number desired, here shown however, as three in number and designated 18, 19 and 20 respectively. These apertures receive the shanks of locking pins designated 21, 22, and 23 respectively, each provided on its upper end with a head 24 which heads are engaged by a block 25 carried by a spring arm 26 attached to the underneath face of the top wall 11 of the casing.

The pin receiving and supporting bar 17 is provided on its under side with a cut away portion 27 of a depth and width corresponding to the depth and width of the locking bar or bolt 28 which locking bar or bolt is provided with apertures 18', 19', 20' adapted to be brought into registry with the apertures 18, 19, 20 in the bar 17 as will be more fully described. The locking bolt at its forward ends is adapted to be projected through an opening 29 provided therefor in the front end wall 14, the projecting end 28' being received in the usual keeper 30, and the bolt being limited in its outward movement by means of a shoulder 31 on its under side which engages with the front wall 14.

The key is inserted into the lock for unlocking the same through an opening 32 provided therefor in the rear end wall 15, this opening being of a height which will permit of vertical movement of the key as will be later explained, the key as shown in Fig. 8 is in the form of a bar 33 having as many pins 34 near its outer end as there are locking pins employed. In Fig. 1 the locking bolt 28 is shown in the locked position. To unlock the bolt the operator places the key in the position shown in Fig. 1 with the pins 34 directly underneath the pins 21, 22, 23. The key is then lifted vertically to the position shown in Fig. 2, causing pins 34 to raise the locking pins 21, 22, 23 out of the pin openings in the pin bar 17. When the locking pins have thus been raised, and while they are held in this raised position by the key, the latter is drawn rearwardly to move it to unlocked position as shown in

- Fig. 3. When in this position and the key is dropped or lowered, locking pin 21 will be held supported by the locking bolt, but pins 22 and 23 will drop by reason of the apertures therefor in the bar 17 and locking bolt 28 being in registry, thus locking the lock bolt in the retracted position, necessitating the insertion of the key, and its positioning underneath the pins 22, 23 so as to raise the same to allow the locking bolt to be again projected or moved into locked position. In this releasing of the pins 22 and 23, the idle pin 34 of the key enters the idle pin receiving aperture 20 in the locking bolt 28, and when pins 22 and 23 have been elevated the locking bolt is pushed forward to locking position by means of the key, the latter then lowered and withdrawn from the locked casing.
- 20 The lock bolt 28 is supported for sliding movement in the cut away portion 27 of the bar 17 by supporting ledges 35 and 36 carried by the rear plate 10 and the front or cover plate 16 respectively.
- 25 While I have described a preferred and practical embodiment of the invention as has been practised by me it will be evident that changes may be made in the details of construction without departing from the spirit or scope of the invention as claimed.
- 30

Copies of this patent may be obtained for five cents each, by addressing the "Commissioner of Patents,
Washington, D. C."

What I claim is:—

1. In a lock, a casing, a longitudinally extending supporting bar therein provided with a series of apertures, headed locking pins mounted in the apertures, a bodily and tiltably yielding presser block coacting with the pins, a locking bolt slidably mounted within the bar, and having apertures corresponding in number to the apertures in the bar and arranged when brought into registry therewith to receive the locking pins.

2. In a lock, a casing, a longitudinally extending supporting bar therein, cut-away on its lower side and having a plurality of openings therethrough, a locking bolt slidably mounted in the cut-away portion and having openings corresponding in number to the openings in the bar, headed locking pins in the openings, a bodily and tiltably yielding presser block engaging the heads of the pins, and a shoulder on the locking bolt to limit its range of movement in locking directions.

In testimony whereof I affix my signature in presence of two witnesses.

FRANK KOSINSKY.
